2,087,467

CENTRIFUGAL SPINNING DEVICE

Thomas H. Byron, Elizabethton, Tenn., assignor
to North American Rayon Corporation, New
York, N. Y., a corporation of Delaware

Application July 30, 1934, Serial No. 737,499

3 Claims. (Cl. 117—27.5)

My present invention relates to the manufacture of yarn of cellulosic origin but more specifically has for its object the continuous treatment and drying of yarn produced in the spinning pot process.

In the manufacture of artificial silk, a spinning solution of cellulosic origin is made up and extruded through the orifices of a spinning nozzle into a coagulating or precipitating medium. The filaments thus formed are drawn therethrough and passed to a spinning pot which simultaneously twists and collects the yarn.

The resulting yarn body of the spinning pot process is built up from outside to inside and when finished has the form of a dough-nut with a rectangular cross-section. This cake of yarn must be given different after-treatments such as desulphurizing or decopping, deacidifying, etc. Due to its structure it has been the practice to use inserts, such as resilient collars, for the purpose of reinforcing the unsupported yarn body during the different treatment steps. Even then the yarn body was not sufficiently supported and a loss was suffered from collapsed cakes or tangled yarn layers.

In view of the foregoing, it is readily apparent that the less handling the spinning cakes receive the less resulting loss there will be through damaged cakes.

After the wet-treatment of the cakes, they must be dried. It is during the drying step that inequalities in the yarn take place, due to uneven shrinkage. It has therefore been the practice to overcome this disadvantage by rewinding the yarn. By so doing an additional step is necessary which increases the production cost.

It is therefore one object of the present invention to lower the cost of production while improving the quality of the yarn.

Another object of the present invention is to produce pot-spun yarn or filaments in a continuous process.

A further object of the present invention is to so produce pot-spun yarn that a twisted, treated and evenly dried product is obtained with a minimum of steps.

These and other objects will in part become obvious and in part be pointed out in the following specification and claims when taken in conjunction with the attached drawing, which:

Figure I is a diagrammatic side elevation of one form of the invention.

Figure II is an enlarged cross-sectional view of my container for the drying of pot-spun yarn which has not already been dried.

Figure III is a detailed cross-sectional view of the cover used with the container shown in Figure II.

In the drawing in which like numerals of reference indicate like parts, and referring specifically to Figure I of the drawing, 1 indicates the yarn or filament bundle which is extruded from the spinneret 2, located below the surface of a precipitating bath 3.

The filaments are drawn upwardly by the roller 5, over a guide roller 4. The drawing roller 5 rotates in a desulphurizing or decopping bath 6 in the trough 7. A flowing bath arrangement (not shown) may be employed at this point, with the bath flowing over the entire surface of the roller 5 and being drained near the top of the trough 7.

From the drawing roller 5 the yarn is led to the second roller 8, rotating, for example, in a washing bath 9 contained in the trough 10. This roller 8 and trough 10 may also have applied the flowing bath arrangement described with respect to the first roller 5. Further, should the type of yarn being treated require more than two baths, these may be added without altering the scope of the present invention.

From the roller 8 the yarn is led over the roller guide 11 and then downwardly to the collecting pot 15. On the way downward the yarn passes through a heating tube 12, having perforations shown at 13. Here warm air or other drying medium is applied to the traveling yarn. The filaments finally pass through the ordinary reciprocating guide indicated by 14, to form the cake 16.

In operation the roller 8 may revolve at a faster rate of speed than the take-up roller 5, thereby stretching the yarn. A further advantage lies in the fact that by rotating the roller 8 at a faster speed than the speed of the take-up in the pot 15 the yarn will be under no appreciable tension when passing through the drying tube 12 and will therefore be able to shrink freely.

The yarn thus wet treated and partially dried is collected in the pot 15. In Figures II and III I have shown a means for drying the yarn thus produced so that no outside-inside shrinkage difficulties occur. The pot 15 is perforated in the bottom portion at 17 and, after collection, a top 18 is applied to the cake. This top 18 comprises a non-foraminous ring provided with a gasket 19, and the ring and gasket are so sized that they snugly fit the inner perpendicular surface face of the pot 15. A drying medium is passed upwardly through the perforations 17 and outwardly

through the orifice 20 in the ring 18. Thus, the top, bottom and sides of the cake are sealed from the action of the drying medium, and the cake 16 is dried from the inside only.

5 In Figure III I have shown a detailed view of the ring 18, and a particular soft gasket 19 with a hollow space 21 is described. This gasket arrangement will be found to be sufficiently rigid to produce a fluid tight seal for the top of the cake 16, and will also be adapted to sink with the cake should it shrink in size longitudinally during the drying step.

10 The ring 18 may be of bakelite, hard rubber, non-corrodible metal, or other material not acted upon by the yarn.

15 Having now set forth my invention as required by the patent statutes, what I desire to claim is:

1. A mechanism for drying yarn so that shrinkage differences are eliminated, comprising, in combination, a spinning pot with imperforate walls and bottom at those points contacting with the cake built up therein, perforations in the middle portion of the bottom not so contacted, and an imperforate ring-like cover for the pot, 20 the imperforate portion being so designed as to seal the top edge of a spun cake, and the cover so constructed that it is able to form a fluid tight covering for the cake top, yet maintain its con-

10 tact therewith if the cake should longitudinally shrink, during its drying.

2. A device for drying yarn so that shrinkage differences are eliminated, comprising, in combination, a spinning pot having a side wall and bottom for contacting a cake built up therein, and a cover for said pot adapted to rest on the top of the spun cake, said cover being so constructed and arranged at its outer periphery as to form a fluid tight seal with the side wall of said pot yet slideable whereby should the cake shrink longitudinally during the drying thereof the said cover will maintain contact with the cake.

3. A device for drying yarn so that shrinkage differences are eliminated, comprising, in combination, a spinning pot having a side wall and bottom for contacting a cake built up therein, and an imperforate cover adapted to rest on the top of the spun cake, said cover having an opening in the center of that portion which is not in contact with the cake, means formed at the outer periphery of said cover to effect a fluid-tight seal with the side wall of said pot, said means adapted to allow the cover to slide along the side wall of said pot whereby should the cake shrink longitudinally during the drying thereof the cover will maintain contact with the cake.
